CARL H. MILLER, OF CLEVELAND, OHIO.

VALVE MECHANISM FOR GAS.

1,010,665.

Specification of Letters Patent.

Patented Dec. 5, 1911.

Application filed January 14, 1910. Serial No. 538,158.

To all whom it may concern:

Be it known that I, CARL H. MILLER, citizen of the United States, residing at Cleveland, in the county of Cuyahoga and State of Ohio, have invented certain new and useful Improvements in Valve Mechanism for Gas, of which the following is a specification.

My invention relates to improvements in valves to control the flow of gases or fluid under pressure but especially gas as it is used with burners, and the invention consists in a valve mechanism adapted to equalize or proportion the flow at the orifice to the volume or quantity of gas admitted past the valve therein, all substantially as shown and described and particularly pointed out in the claims.

In the accompanying drawings, Figure 1 is a side elevation of the device partially sectioned in its connections, and Fig. 2 is a longitudinal sectional elevation of the body member and associated parts.

In valve mechanism to supply gas to a burner, say such as is used in a kitchen range, it is important that at least two common objections or defects be avoided, namely, the blowing and the sputtering of the gas. Both of these conditions are highly objectionable in such a connection as well as in all others wherein it occurs, and the object of this invention is to prevent such results or rather to provide a construction wherein they cannot occur.

Thus, in the drawing, B represents the body of the valve having a longitudinal bore for the valve stem C considered as a whole and a fluid inlet 2 at one side to said bore. The said bore is differential or of two diameters or sizes in cross section, the larger portion extending through from the one end across said inlet to valve seat 3, and the smaller portion extends from said valve seat to the other end of the said bore and which is its orifice or discharge end. Now, having a body B of this construction or substantially as shown and described for practical purposes, I employ a valve stem C which also may be said to be of different sizes in its cross sections corresponding to said bore, and provided with a thread 4 on its larger portion 5 adapted to engage the thread in the larger portion of said body, and a reduced portion 6 corresponding to the smaller portion of said bore and having what may be termed a needle point 7. A valve 8 is formed

on stem 5 at the entrance to said smaller bore and adapted to occupy said valve seat 3, and the extremity or point 7 of the said stem projects out beyond the end of body 60 B relatively as shown. This projection is however only incidental, in a sense, because of a reducing plug 9 inserted in said body, or screwed into the thread therein at this end and projecting outward beyond the said end 65 of the body a sufficient distance to obtain the desired control of the gas at this point. This control is relative and is designed to be proportional to the position of valve 8. For example, and as a matter of experience, I 70 should explain here that the sputtering of the gas at the orifice and the blowing which always is objectionable is designed to be partially controlled by the adjustments which plug 9 affords. It will be noticed that 75 said plug has a bore for the reduced portion 6 of the valve stem which gradually tapers inward to its orifice and so that as the said plug is adjusted it may more or less closely approach to the tapered point 7. It is not 80 intended that said orifice shall ever be wholly closed because point 7 is not a valve but a passage reducing member working in conjunction with the said plug 9, and the object is to proportion the issue of the gas 85 past or about said point to the volume admitted past valve 8. I have found that if what may be termed uniformity of issue or pressure be maintained at these two points and having a proper adjustment to begin 90 with there is no blowing and no sputtering however much or little gas is used. Hence if a full head of gas be used the orifice at point 7 is opened correspondingly wide by withdrawing the valve stem. Then as the 95 quantity used is to be reduced the said stem is turned inward which will cause point 7 to enter the said orifice more or less and correspondingly reduce the volume of the outflow. But the proportions with the gas 100 admitted will be maintained and there will be only a gradual reduction of the flame and nothing more, and in no case does reducing point 7 wholly close the orifice.

In the present instance I have shown this 105 device in connection presumably with a range or stove as indicated by part D, but it may be used wherever it is found useful.

It will be seen from the foregoing that the discharge orifice for the gas is under positive control by means of the valve stem and is reduced but never entirely closed with the

shutting down of the gas and enlarged as the valve is opened. The area of said discharge orifice is therefore always changing with the valve and dependent thereon, and plug 9 is set according to conditions of the gas flow and need not be changed unless conditions of operations change, such as more or less gas pressure or possibly according as to whether artificial gas be used.

10 What I claim is:

1. In gas feeding mechanism for cooking ranges and the like, a body having a bore of two diameters through its center and a valve seat where said diameters change and an inlet for gas in advance of said seat, a plug with a tapered orifice adjustable in the outer end of said bore, in combination with a hand controlled valve stem having a valve adapted to engage said seat and shut off the flow of gas and provided with a spindle projecting through the smaller portion of said bore from said valve and having a tapered reducing point entering the said tapered orifice and limited to a partial closing of said orifice.
- 25

2. In valve mechanism adapted to control the flow of gas, a body having a bore of two sizes and a valve seat at the point where said bore changes in size from its larger to its smaller diameter, a tubular reducing plug 30 fixed in the outer portion of said smaller bore provided with an orifice of gradually reduced cross section from its inner to its outer portion, a valve stem provided with a tapered valve between its ends adapted to close said 35 valve seat and a reduced outer end having a tapered point adapted to partially close said tapered orifice, said reducing plug being adjustable lengthwise to regulate the flow of gas through the same to correspond to the 40 volume of gas admitted through said valve and to remain open when said valve is closed.

In testimony whereof I affix my signature in presence of two witnesses.

CARL H. MILLER.
